INCUBATOR

Matthew J. Duffy, Chicago, Ill., assignor to Handi-Premature Carrier Company, Chicago, Ill., a copartnership

Application October 26, 1946; Serial No. 705,935

8 Claims. (Cl. 128—1)

1

This invention relates to incubators, and more particularly to incubators of the type especially adapted to be used in the care of premature infants.

As is commonly known, new born infants, and especially those prematurely born, are often so frail and weak that special care must be used to insure that proper temperatures of the air surrounding them be maintained within relatively narrow limits, and to insure that the infant be protected from drafts. To this end, hospitals and like institutions have heretofore employed specially air-conditioned rooms and incubators. The air-conditioned rooms have the disadvantage, of course, among others, of being immovable from a fixed location, and the incubators heretofore known, some of which have been portable or semi-portable, have the disadvantage of being complex in structure and operation. It is the primary object of my invention to provide an improved incubator, especially adapted for the care of premature infants, which is safe and efficient in use, and which is simple both in construction and operation.

It has often been found that when infants have been born in private homes, or in other places away from a suitably equipped hospital, that the infant must be rushed immediately after birth to a hospital for proper care and treatment. This is especially true in the case of infants born prematurely. Unfortunately, the period immediately following the birth of an infant, and especially a premature infant, is one of the most critical times in the proper protection of the infant from cold and drafts. Therefore, if, during this time, it is necessary to transport the infant from a private home, or the like, to a hospital, or similar institution, the protection of the infant from cold and drafts poses a difficult problem. This is especially true when the outside

temperature is low such as, for example, during the winter time, because of the difficulty involved in properly controlling the temperatures to which the infant is subjected and to protect the infant from dangerous drafts. Hospitals, and the like, have resorted to many different devices in attempting to protect the new-born infants while they are being transported by ambulance to the hospital. However, the devices heretofore known have had many disadvantages such as, for example, being cumbersome to handle or use, complicated in construction and operation, delicate in construction so that they are easily broken or thrown out of adjustment, or inefficient and unreliable. It is an object of my invention to con-

2

struct an incubator for infants which is compact, light in weight, easily handled, simple to operate, simple in construction, and efficient and reliable in operation.

It is a further object of my invention to provide an incubator for infants which can be used efficiently either as a stationary or portable unit. Still a further object of my invention is to provide an incubator for infants which can be easily handled and manually transported, by one attendant, while an infant is in incubating position within the incubator.

Another object of my invention is to construct an electrically heated incubator for infants which can be operated from the usual electric power source in a private home and also from a suitable electric power source in an ambulance or the like.

Yet a further object of my invention is to so construct an incubator that an infant, when placed therein, can be adequately protected from drafts.

Another object of my invention is to construct an incubator for infants in such a manner that, if so desired, the space within which an infant is placed may be illuminated by diffused light from the normal operation of the heating devices for the incubator.

Because of their frailty, prematurely born infants and sick or ailing infants often have difficulty in breathing sufficient air to sustain life, and breathing-oxygen must be supplied to them. The supplying of oxygen to infants is often a difficult problem, especially when it is necessary to transport the infant to a hospital and particularly when transporting the infant to and from the ambulance. In this connection it is an object of my invention to provide a portable incubator for infants wherein a supply of breathing-oxygen, and apparatus for feeding the same to the infant, may be carried as an integral part thereof.

Another object of my invention is to construct an incubator for infants wherein the incubator chamber, the heating unit, the temperature controls, a supply of breathing-oxygen, and controls for regulating the flow of breathing-oxygen into the incubator chamber may all be included in a compact portable unit which is of such size and weight that it may be relatively easily carried by one man.

An object ancillary to the foregoing is to provide an incubator of the afore-mentioned type wherein the temperature controls, supply of breathing-oxygen, and the controls for regulating the flow of oxygen are readily accessible without subjecting an infant, which might be with-

in the incubator chamber thereof, to the danger of drafts.

A further object of my invention is to construct an incubator of the aforementioned character wherein the incubator chamber can be closed against drafts.

Yet another object of my invention is to associate a compound door with the incubator chamber of an incubator for infants in such a manner that it can quickly and easily be opened to provide a relatively large and unrestricted opening through which the infant can be easily placed in, or removed from, the incubator chamber, and wherein, at other times, the door can be quickly and easily closed, either completely or partially, the extent of closing being dictated by the conditions and requirements of each particular case.

Another object of my invention is to construct an incubator which can be quickly and easily cleaned in a thorough manner.

A further object of my invention is to provide an efficient portable incubator for infants which is simple to operate, can be economically and cheaply manufactured, is sturdy in construction, and is reliable in use.

Another object of my invention is to provide a practical and efficient incubator for infants which can be constructed of relatively light sheet metal and wherein the walls thereof have a reflective surface, providing relatively good insulative properties.

Other and further objects of the present invention will be apparent from the following description and claims and are illustrated in the accompanying drawings which, by way of illustration, show preferred embodiments of the present invention and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims.

In the drawings:

Fig. 1 is an exploded perspective view of an incubator for infants embodying the principles of my invention;

Fig. 2 is a top plan view of the incubator shown in Fig. 1, and with the top covers closed;

Fig. 3 is a front elevational view of the incubator shown in Fig. 1, with certain parts broken away;

Fig. 4 is a rear elevational view of the incubator shown in Fig. 1 with certain parts broken away;

Fig. 5 is a vertical sectional view taken substantially along the line 5—5 in Fig. 2;

Fig. 6 is a detail horizontal sectional view taken substantially along the line 6—6 in Fig. 2;

Fig. 7 is a detail bottom plan view taken substantially along the line 7—7 in Fig. 6;

Fig. 8 is a horizontal sectional view taken substantially along the line 8—8 in Fig. 3;

Fig. 9 is a detail vertical sectional view taken substantially along the line 9—9 in Fig. 8;

Fig. 10 is a schematic diagram of the wiring for the heating system used in the incubator shown in Figs. 1 to 9, inclusive; and

Fig. 11 is a schematic diagram of the wiring for the heating system used in a modified form of my invention.

For purposes of illustration an incubator 20, which embodies the principles of my invention, is shown in the accompanying drawings, and which incubator 20 is formed substantially in the shape of a rectangular box or casing having a bottom wall 22, a front wall 24, a rear wall 26, end walls 28 and 30, two compound doors 32 and 33 and a longitudinally extending door 35, the three doors 32, 33 and 35 comprising the main portion of the top wall unit of the incubator 20. Runners 36 and 37 are attached to the bottom wall 22 by suitable means such as bolts 38 and act as supports for the incubator 20.

In general, the incubator 20 comprises an incubator chamber 40, into which an infant may be placed and from which an infant may be removed through the top of the incubator 20 when the doors 32 and 33 are open; a heater chamber 41, disposed below the incubator chamber 40 and separated therefrom by a baby-supporting panel 43; and an auxiliary chamber 44 extending longitudinally of the incubator 20 and disposed laterally from the incubator chamber 40 and the heater chamber 41, and separated therefrom by a vertical, longitudinally extending partition 45.

The front edge portion of the end walls 28 and 30 are bent substantially transversely to form flanges 47 and 48, respectively, which are secured to the respective adjacent end edge portions of the front wall 24 by suitable means such as rivets 49. Similar rear flanges 50 and 51 are formed at the rear edge portion of the end walls 28 and 29, respectively, and are attached to the respective end edge portions of the rear wall 26 by suitable means such as rivets 52.

Likewise, as is best shown in Fig. 4, the lower edge portion of the end walls 28 and 30 are bent transversely to form flanges 54 and 55 which are attached to the respective adjacent edge portions of the bottom wall 22 by suitable means such as rivets 56.

The front wall 24, the bottom wall 22 and the rear wall 26 are formed of one piece of material and may be formed by a bending operation in a manner well known to the art.

In the manufacture of my incubator, I prefer to make the front wall 24, the bottom wall 22, the rear wall 26, the end walls 28 and 30, the doors 32, 33 and 35, the panel 43 and the partition 45 of my incubator 20 from reflective, relatively light sheet metal such as, for example, sheet aluminum having a thickness of eighty-thousandths of an inch, although other suitable materials, and other thicknesses may be used without departing from the purview of my invention. Forming the incubator 20 from aluminum, as I prefer to do, has the advantage of providing a structure which is light in weight and, also, one which is reflectively insulated to a considerable extent.

The baby-supporting panel 43 comprises a top wall 58 and substantially vertically disposed side walls or supporting legs 59 and 60 which depend from the longitudinal edge portion thereof. As is best seen in Fig. 5, when the panel 43 is in position of use within the incubator chamber 40, the supporting legs 59 and 60 rest on the bottom wall 22 of the incubator 20 and support the top wall 58 of the panel 43 in spaced relation thereto. As is best seen in Fig. 8, a wire handle 61 is pivotally attached to the upper surface of the supporting panel 43 by a bracket 62 and can be easily grasped by the operator to remove the panel 43 from the incubator chamber 40 when it is desired to re-

move the same in cleaning the interior of the incubator 20, or for any other purpose. The top wall 58 of the infant-supporting panel 43 has perforations 63 formed therein for purposes which will be presently explained.

A substantially channel-shaped auxiliary supporting panel 65, having a top wall 67 and depending side walls or supporting legs 69 and 70, is mounted in the auxiliary chamber 44 and secured to the bottom wall 22 thereof by suitable means such as bolts 72. As will be presently described in detail, the auxiliary panel 65 provides a conduit for a substantial portion of the electric wiring used in the heating of my novel incubator 20 and also provides a platform on which an oxygen bottle, or the like, may be supported in the auxiliary chamber 44.

As is best seen in Fig. 5, flanges 74 having substantially vertically extending legs 75 and horizontally extending legs 76 are mounted on the upper edge portion of the front wall 24, the end walls 28 and 30 and the partition panel 45 and are secured thereto by suitable means, such as rivets 78. The flanges 74 are attached to the front wall 24, the side walls 28 and 30 and the partition 45 in such a manner that the horizontally extending legs 76 project inwardly toward the center of the incubator chamber 40, and each of the horizontally extending legs 76 has an arcuate groove or channel formed in the upper surface thereof in which is positioned a resilient cord 80 for weather-stripping purposes.

The doors 32, 33 and 35 are carried by a supporting frame 82 which is adapted to rest on and be supported by the upper edge portion of the front wall 24, the rear wall 26, the end walls 28 and 30, and the partition 45 of the incubator 20. The frame 82 comprises a front member 84, end members 85 and 86, a rear member 88 and a longitudinally extending partition member 90. The front member 84 is attached to the front end portions of the end members 85 and 86, and the rear member 88 is attached to the rear end portions of the rear end members 85 and 86 by suitable formed corner members 92 secured in place by suitable means such as rivets 94, the longitudinally extending partition member 90 being secured in place by suitably attaching the end portions thereof to the end members 85 and 86 by suitable means such as, for example, by soldering.

The front member 84, the side members 85 and 86 and the longitudinal member 90 of the frame 82 are each shaped somewhat similarly to the flanges 74 and have downwardly extending legs 96 and horizontally extending legs 97, the latter of which are adapted, when the frame 82 is in position on the incubator 20 to overlie and contact the resilient cords 80. The rear member 88 of the frame 82 has a vertically extending leg 99 and a curved, substantially horizontally extending leg 100 and is adapted to rest on the upper end portion of the rear wall 26 when the frame 82 is in assembled position on the incubator 20. Suitable latches 102, adapted to hold the frame 82 in position on the incubator 20, and which are well known to those skilled in the art, are mounted on the front wall 24 of the incubator 20 and the front member 84 of the frame 82, and similar latches 104 are mounted on the rear wall 26 and the rear member 88.

The compound door 32 has two panels 106 and 107 connected together by a hinge 109 and the door 32 is hingedly connected to the end member 85 of the frame 82 by a hinge 110 connected

to the outer end portion of the door panel 107. Similarly, the compound door 33 has two panels 112 and 113 connected together by a hinge 115 and is connected to the end member 86 of the frame 82 by a hinge 117 which is attached to the outer end portion of the door panel 113. The door 35 is of the single panel type and is connected to the rear member 88 of the frame 82 by a hinge 119.

It will be noted that the compound doors 32 and 33 may be completely opened so as to allow substantially unrestricted access to the incubator chamber 40 by pivoting the doors 32 and 33 on the hinges 110 and 117, respectively, or they may be opened partially by pivoting the panels 106 and 112 thereof around the hinges 109 and 115, respectively. As best seen in Figs. 2 and 6, the free end portion 121 of the door 33 extends beyond the center line between the end members 85 and 86 of the frame 82 and is formed to overlie the free end portion of the door 32 when the doors 32 and 33 are in fully closed position.

A latching member 123, having a knob 125 and a downwardly extending screw threaded shaft 127 to which is non-rotatably secured, by a nut 129 and washer 130, a latching element 132, is carried by the door 33 and is adapted to retain the doors 32 and 33 in closed position relative to each other when the latching element 132 is turned in such position as to underlie the door 32, as shown in Fig. 6, and as shown in solid lines in Fig. 7. The latching member 123 may be released from latching engagement with the door 32 by turning the knob 125 so as to position the latching element 132 in the position shown in dotted lines in Fig. 7, thereby releasing it from engagement with the door 32. The door 35 also carries two latching members 133 and 134, which are similar to the latching member 123 and are similarly operable to releasably hold the door 35 in latched engagement with the longitudinal member 90 of the frame 82.

Glass inspection panels 135 and 136, Figs. 1, 2 and 5, comprising panes of glass 138 and 139 are mounted in openings 140 and 141, respectively, in the door panels 107 and 113, respectively, and are held therein by frame members 142 and 143, which are attached to the door panels 107 and 113, respectively, by any suitable means such as screws 144. The inspection panels 135 and 136 are so mounted in the compound doors 32 and 33, respectively, that when an infant is in position within the incubator chamber 40 and the doors 32 and 33 are in fully closed position, the operator may view the infant and suitable temperature indicating devices, which may be placed within the chamber 40, without opening the doors 32 and 33.

As is best seen in Figs. 1, 4 and 8, a suitable electric socket 146 which is adapted to receive the prongs of a connecting plug on the end of an electric cord such as the cord 146a, shown in Fig. 8, is mounted in the lower end portion of the end wall 28 of the incubator 20 adjacent to one end of the auxiliary chamber 44, and is suitably electrically connected, in parallel, to sockets 148 and 149 in which may be mounted light bulbs 151 and 152, respectively. The end portions of the sockets 148 and 149 into which the light bulbs 151 and 152 may be screwed extend through suitable openings formed in the partition 45 and the other end portions thereof extend through and are secured to the downwardly extending leg 69 of the auxiliary supporting panel 65 by means of nuts 154. Switches 156 and 157 are mounted on

the respective end walls 28 and 30 on suitable flanges 159 and 160, respectively, and are adapted to control the parallel circuits to the bulbs 151 and 152, respectively.

As is best seen in Fig. 8 and the wiring diagram shown in Fig. 10, electricity is supplied to the bulb 151 from the plug 146 through a main power line 162, a branch line 163, switch 156, a branch line 164, the socket 148, a branch line 165, and a main power line 166, and electricity is likewise supplied to the bulb 152 from the plug 146 through the main power line 162, a branch line 168, the switch 157, a branch line 169, the socket 149, a branch line 170 and the main power line 166. The lines 163 and 164 leading from the power line 162 to the switch 156, and from the switch 156 to the socket 148, respectively, extend upwardly through an opening 172 formed in the top wall 67 of the auxiliary panel 65 to the switch 156 which is mounted in the upper end portion of the auxiliary chamber 44. Likewise the lines 168 and 169 which connect the power line 166 to the switch 157, and the switch 157 to the socket 149, respectively, extend upwardly through an opening 174 formed in the top wall 67 of the supporting panel 65 to the switch 157 which is also mounted in the upper portion of the auxiliary chamber 44.

As is best seen in Figs. 8 and 9, insulating members 176 having suitable sheet metal covers 178 and liners 179 are attached to the lower surface of the upper wall 58 of the infant-supporting panel 43 by suitable means such as rivets 181 directly above the light bulbs 151 and 152, respectively. The insulating liners 179 of the insulating panels 176 may be made of any suitable material such as, for example, asbestos. The insulating panels 176 act both as heat shields and light reflectors so that extremely warm "hot spots" are not formed on the portions of the infant-supporting panel 43 positioned directly above the light bulbs 151 and 152, respectively, and also so that light does not shine upwardly directly from the light bulbs 151 and 152 through openings 63 formed in the supporting panel 43.

As is best seen in Figs. 3 and 8, an opening 183 is formed in the central lower end portion of the front wall 24 through which light bulbs 151 and 152 may be placed in, and removed from, the sockets 148 and 149, respectively, when it is undesirable to open the doors 32 and 33 and remove the supporting panel 43 during certain times such as, for example, when an infant is in position within the incubator chamber 40. A removable panel 185 is normally positioned over the opening 183 and secured to the front wall 24 by suitable bolts 187, the panel 185 being removable from the front wall 24 by unscrewing the bolts 187. I prefer to make the opening 183 as small as practicable so that if a light bulb burns out when an infant is in the incubator chamber 40 and it is necessary to remove and replace the burned out bulb, uncovering the opening 183 by removing the panel 185 will provide as small an opening as possible so that the infant will not be subjected to unnecessary drafts. Therefore in the preferred form of my novel incubator 20 the opening 183 is just large enough to readily pass light bulbs such as the light bulbs 151 and 152 therethrough and this, in some instances, will mean that a normal sized adult hand cannot be extended through the opening 183 to remove and replace light bulbs from the sockets 148 and 149. However, mechanical hands or mechanical fingers, such as the type which are used to remove and replace light

bulbs from certain inaccessible light fixtures, and which are well known to the art, may be used for this purpose.

In many instances, new-born infants, and especially those prematurely born, are so frail and weak that it is impossible or difficult for them to breathe a sufficient amount of air to sustain life, and in those instances it is often necessary to supply substantially pure breathing-oxygen to the infant. In the use of my incubator, the supplying of breathing-oxygen to an infant may be easily accomplished by placing an oxygen bottle, such as the oxygen bottle 190, Figs. 2 and 3, in reclining position upon the top of the auxiliary

supporting panel 65 within the auxiliary chamber 44, and feeding oxygen from the bottle 190 in controlled amounts through suitable mechanism such as a valve 191, a regulator 192 and a tube 193 into the incubator chamber 40. Suitable pressure gauges 195 and 196 may be provided to indicate both the pressure of the oxygen in the bottle 190 and the pressure of the oxygen as it is fed to the incubator chamber 40. As is best seen in Figs. 1 and 2, the tube 193 through which the oxygen is supplied from the regulator 192 to the incubator chamber 40 extends through an opening 198 in the longitudinal partition 45 which separates the incubator chamber 40 from the auxiliary chamber 44.

It will be noted that when an infant is in position in the incubator chamber 40 and it is found necessary to operate or change the setting of the oxygen valve 191 or to turn on or turn off the switches 156 or 157, this may be accomplished by opening the door 35 to the auxiliary chamber 44, which operation does not open the incubator chamber 40 and therefore precludes the possibility of thereby subjecting the infant therein to objectionable or dangerous drafts.

Two handles 200 and 201 are attached to the outer surface of the end walls 28 and 30, respectively, by suitable means such as screws 203, and by grasping a handle in each hand one man can easily carry my novel incubator 20 even though an infant is in position within the incubator chamber 40 and a full supply of oxygen is positioned within the auxiliary chamber 44.

In the normal operation of my novel incubator, a suitable pad is placed on the top wall 58 of the infant-supporting panel 43 and the incubator is then pre-heated by connecting the electric plug receptacle 146 to suitable electric power and operating one or more of the bulbs 151 and 152 under the control of the switches 156 and 157, respectively. The doors 32 and 33 are then opened wide and the infant placed on the pad on the supporting panel 43 and the doors 32 and 33 are then closed the desired amount. To protect the infant against objectionable drafts, and also to assist in maintaining the proper temperatures within the incubator chamber 40, it normally will be desired, and especially in chilly or cold weather, to keep the doors 32 and 33 fully closed after the infant has been placed on the panel 43. However, during certain times, and especially during warm weather, it may be desirable to have the doors 32 partly open and this may be easily accomplished by either partly or fully opening the door panels 108 and 112 as desired. Whether to have the doors fully closed or partially open will depend on the circumstances of each individual case and therefore it will be necessary for the operator of the incubator in each case to determine the procedure to be followed.

It will be noted that if a relatively light pad

such as, for example, a blanket, is used on the panel 43 so as to fully cover the top wall 58 thereof, or if a heavier pad is placed on the top wall 58 of the panel 43 in such a manner that all, or a part of, the openings 63 nearest the peripheral edge of the top wall 58 of the supporting panel 43 are left uncovered, light from the bulbs 151 and 152 will be diffused upwardly through the lighter pad, or, if a heavier pad is used, through the uncovered openings 63, and provide diffused illumination within the incubator chamber 40.

When the baby has been placed in the incubator chamber 40, the tube 193 may be positioned so as to closely overhang in front of the baby's face so that oxygen supplied therethrough will surround the head of the infant. The flow of oxygen through the tube 193 may readily be regulated by operation of the valve 191 which, as previously mentioned, may be adjusted within the auxiliary chamber 44 with only the doors 35 being opened and without opening the incubator chamber 40.

Also the temperature within the incubator 40 may be carefully controlled by the attendant or operator by the proper turning on and turning off of the switches 156 and 157 to thereby selectively turn on and turn off the heating elements or light bulbs 151 and 152. This also may be accomplished upon opening the auxiliary chamber 44 only, and without opening the incubator chamber 40. In connection with the control of the temperature within the incubator 40 it will be noted that, for purposes of illustration, I have shown only two light bulbs 151 and 152 connected to the power lines 162 and 166. However, this is for the purpose of illustrating my invention only, and not to limit it thereto, and it will be appreciated by those skilled in the art that more bulbs together with suitable individual control means, similar to switches 156 and 157, may be similarly connected in parallel across the power lines 162 and 163 and mounted in the heater chamber 41 in a manner similar to that employed in mounting the light bulbs 151 and 152 without departing from the purview of my invention.

In the modified form of my invention, as shown in Fig. 11, parts similar to parts shown in Figs. 1 to 10, inclusive, are indicated by like reference numerals with the suffix "m" added thereto. It will be noted that Fig. 11 is a diagrammatic illustration of the modified form of electrical circuit used in heating, and controlling the heating of, the modified form of my incubator and that the construction of the incubator, with the exception of the wiring thereof, is substantially the same as that shown in Figs. 1 to 9 inclusive.

The principal difference between the form of my invention shown in Figs. 1 to 10 and the modified form shown in Fig. 11 is that in the modified form a rheostat 300 is used to control the flow of electric current to the bulbs 151m and 152m. The rheostat 300 may be of any suitable form but I prefer to use one having a power rating of approximately 100 watts, and also, I prefer to mount the rheostat 300 in any suitable manner, such as, for example, by a suitable bracket, not shown, within the auxiliary chamber of the incubator so that the rheostat does not project from the incubator casing. However, it will be appreciated that I state the manner in which I prefer to mount the rheostat 300, for the purpose of illustrating my invention only, and not by way of limitation, and that other rheostats or

other means or manners of mounting the rheostat 300 may be used without departing from the purview of my invention.

It will be noted that the rheostat 300 is connected in series with the power lines 162m and 166m and simultaneously controls the flow of electricity from the plug 146m to the two bulbs 151m and 152m, which are connected in parallel across the power lines 162m and 166m by lines 163m, socket 148m and line 165m, and line 170m, socket 152m and line 168m, respectively.

From the foregoing it will be apparent that I have provided a novel incubator which may be used either as a stationary or portable incubator for infants and is especially adapted for the proper incubation of frail infants such as, for example, those prematurely born, during the trip when it is found necessary to transport them to a hospital.

Also it will be noted that my incubator 20 may be connected to electric power sources found in the normal private home, and may also be similarly connected to a suitable power source within an ambulance or the like while transporting an infant by ambulance to or from a hospital.

Also it will be noted that after an infant has been placed in the incubator chamber 40 and the incubator 20 heated to the proper temperature, the incubator 20 provides a practical and safe means of transporting the infant to and from an ambulance, being sufficiently light and easily handled for this purpose and also being suitably insulated so that the temperature within the incubator chamber 40 will be maintained relatively constant during this time. Also during the transporting of the infant to and from the ambulance within the incubator chamber 40 it will be noted that my incubator provides a practical and safe protection of the infant from dangerous drafts.

Furthermore, it will be noted that although the walls of my incubator are comparatively thin and are made from light material so that the incubator may be quickly and easily handled by a nurse or other attendant, relatively good reflective insulating qualities are provided therein by forming the incubator 20 from aluminum or, if it is formed from less reflective material, coating the inside and outside thereof with a reflective coating such as aluminum-colored paint.

In addition it will be noted that when an infant is within the incubator chamber 40 and the doors 32 and 33 are closed, the infant may be easily viewed through the inspection panels 135 and 136, as may temperature indicating devices which may be placed within the chamber 40.

Also it will be noted that after the infant has been placed in the incubator chamber 40 and the doors 32 and 33 thereof are closed, the flow of oxygen to the infant and the temperature of the incubator chamber 40 may be regulated without opening the incubator chamber 40 and thereby subjecting the infant to possibly dangerous drafts.

Hence, while I have illustrated and described the preferred embodiments of my invention, it is to be understood that these are capable of variation and modification and I therefore do not wish to be limited to the precise details set forth, but desire to avail myself of such changes and alterations as fall within the purview of the following claims.

I claim:

1. An incubator comprising a casing having an open upper end, means dividing said casing into three chambers, two of said chambers being po-

sitioned vertically one above the other and the third chamber being positioned horizontally from the other two, one of said means for dividing said casing comprising a substantially vertically extending partition positioned between said third chamber and said other two chambers, a closure member releasably mounted on said upper end of said casing for closing said upper end, weatherstripping means engageable between said closure member and the upper end portion of said casing and partition, electrically operated members mounted within the lower one of said two chambers for heating the upper one of said two chambers, and means mounted in said third chamber and operatively connected to said electrically operated members for controlling the operation of said electrically operated members.

2. An incubator comprising a closable casing having three chambers defined therein, two of said chambers being positioned vertically one above the other and the third chamber being positioned horizontally from the other two, a supporting member adapted to support an infant within the upper of said two chambers, electrically operated heating means mounted within the lower of said two chambers for heating said upper chamber, said third chamber being adapted to hold a supply of oxygen for feeding oxygen to said upper chamber, and means movably mounted on said casing for selectively opening and closing said upper chamber and said third chamber to the atmosphere.

3. An incubator comprising a closable casing comprising a bottom wall, side walls secured to said bottom wall and extending upwardly therefrom and a top wall unit removably mounted on said side walls, a partition member extending upwardly from said bottom wall interiorly of said casing and dividing said casing into two parts, means for supporting an infant within one of said parts, and means for heating said one part, said last mentioned means extending through said partition member from the other of said parts to said one part, said top wall unit comprising a frame and door means carried by said frame, said door means being movable to open or close said top wall unit and said casing.

4. An incubator for infants comprising a casing, said casing comprising a bottom wall, side walls extending upwardly from said bottom wall, and a top wall unit mounted on said side walls operable to be opened and closed in segments to thereby correspondingly open and close said casing, a partition member extending upwardly from said bottom wall and horizontally dividing said casing into two parts, a supporting member carried by said casing for supporting an infant within one of said parts, an auxiliary supporting member carried by said casing within the other of said parts for holding a supply of oxygen in said other part, an electrically operated heater element positioned within said one part for heating said one part, and means below said auxiliary supporting member and extending through said other part and said partition member for feeding electricity to said heater element, and means comprising a passageway through said partition member for feeding oxygen from such a supply in said other part into said one part, one of said segments of said top wall being movable into open and closed position for selectively opening and closing said other part without opening said one part to thereby afford access to said electricity feeding means and such a supply of oxygen without opening said one part.

5. An incubator for infants comprising a clos-

able casing, said casing comprising a bottom wall, side walls carried by said bottom wall and extending upwardly therefrom, and a top wall unit removably mounted on said side walls and operable to be opened and closed in segments to thereby correspondingly open and close said casing, said bottom wall, side walls and top wall unit being made of light-reflective material, a partition member extending upwardly from said bottom wall and horizontally dividing said casing into two compartments, a horizontally extending panel member carried by said bottom wall and adapted to support an infant within one of said compartments, an auxiliary supporting member carried by said bottom wall within the other of said compartments and adapted to hold a supply of oxygen within said other compartment, electrically operated and parallel-connected heating members positioned in said one compartment between said bottom wall and said horizontally extending panel member, electrically conductive means carried by said casing and extending between said auxiliary supporting member and said bottom wall and extending through said partition member for carrying electricity to said heater members, said electrically conductive means being adapted to be connected to an electric power source positioned exteriorly of said casing, and manually operable control means mounted in said other compartment above said auxiliary supporting panel and connected to said conductive means for controlling the flow of electricity through said conductive means, said top wall being operable during said opening and closing in segments to selectively open and close said one compartment and said other compartment.

6. An incubator for infants comprising a closable casing, said casing comprising a bottom wall, side walls carried by said bottom wall and extending upwardly therefrom, and a top wall unit removably mounted on said side walls and operable to be opened and closed in segments to thereby correspondingly open and close said casing, said bottom wall, side walls and top wall unit being made of light-reflective material, a partition member extending upwardly from said bottom wall and horizontally dividing said casing into two compartments each of which is disposed directly under a respective one of said segments of said top wall and in vertical registration therewith when said segments are closed, a horizontally extending panel member carried by said bottom wall and adapted to support an infant within one of said compartments, electrically operated and parallel-connected heating elements positioned in said one compartment between said bottom wall and said horizontally extending panel member, electrically conductive means carried by said casing and extending through said partition member for carrying electricity to said heater elements, and manually operable switch means connected in parallel to each other for individually controlling said heater elements, said switch means being mounted in the other of said two compartments below said respective segment of said top wall in position whereby said switch means is manually operable through the top of said other compartment when said last mentioned segment is disposed in open position.

7. An incubator for infants comprising a closable casing, said casing comprising a bottom wall, side walls carried by said bottom wall and extending upwardly therefrom, and a top wall unit removably mounted on said side walls and operable to be opened and closed in segments to

13

thereby correspondingly open and close said casing, said bottom wall, side walls and top wall unit being made of light-reflective material, a partition member extending upwardly from said bottom wall and horizontally dividing said casing into two compartments and having an opening therein, a horizontally extending panel member carried by said bottom wall and adapted to support an infant within one of said compartments, an auxiliary supporting member carried by said bottom wall within the other of said compartments for supporting a supply of oxygen in position in said other compartment for feeding oxygen through said opening into said one compartment, electrically operated and parallel-connected heating members positioned in said one compartment between said bottom wall and said horizontally extending panel member, electrically conductive means carried by said casing and connected to said heating members for carrying electricity to said heater members, and a rheostat connected to said electrically conductive means and operable to simultaneously control the flow of electric current to each of said heating members, said electrically conductive means being adapted to be connected to an electric power source positioned exteriorly of said casing, one of said segments of said top wall being disposed over said other compartment in vertical registration therewith for thereby selectively opening and closing said other compartment for permitting access to such a supply of oxygen without opening said one compartment.

8. An incubator comprising a casing having three chambers defined therein, two of said chambers being positioned one above the other and the third chamber being positioned horizontally from the other two, said casing comprising a bottom wall, side walls secured to said bottom wall and extending upwardly therefrom, and a door unit mounted on said side walls and adapted

14

to be actuated to open and close said casing, a partition member extending upwardly from said bottom wall and forming a wall between said two chambers and said third chamber, said partition member having an opening formed therein, a supporting member mounted on said bottom wall and forming a dividing wall between said two chambers, said supporting member being adapted to support an infant in the upper one of said two chambers, an electrically operated heating member mounted in the lower one of said two chambers, means extending through said third chamber and through said partition wall for feeding electricity to said heating member, and an auxiliary supporting member mounted in said third chamber above the level of said heating member, said auxiliary supporting member being adapted to support a container of oxygen within said third chamber from which container oxygen may be fed through the opening in said partition member into the upper one of said two chambers.
